US0D1072928S

(12) **United States Design Patent** (10) **Patent No.:** **US D1,072,928 S**
(45) **Date of Patent:** **** Apr. 29, 2025**

(54) **POS TERMINAL**

- (71) Applicant: **POSBANK CO., LTD.**, Seoul (KR)
(72) Inventor: **Dong-Uk Eun**, Gwangmyeong-si (KR)
(73) Assignee: **POSBANK CO., LTD.**, Seoul (KR)
(**) Term: **15 Years**
(21) Appl. No.: **29/883,319**
(22) Filed: **Jan. 26, 2023**

(30) **Foreign Application Priority Data**

- Jan. 11, 2023 (KR) 30-2023-0001279

(57) **CLAIM**

The ornamental design for a POS terminal, as shown and described.

DESCRIPTION

FIG. 1 is a perspective view of a POS terminal, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view from a different angle thereof;

FIG. 9 is a perspective view of the POS terminal in an alternate position;

FIG. 10 is a front view thereof in the alternate position;

FIG. 11 is a rear view thereof in the alternate position;

FIG. 12 is a left-side view thereof in the alternate position;

FIG. 13 is a right-side view thereof in the alternate position;

FIG. 14 is a top view thereof in the alternate position;

FIG. 15 is a bottom view thereof in the alternate position; and,

FIG. 16 is further another perspective view from another different angle thereof in the alternate position.

1 Claim, 16 Drawing Sheets
